UNITED STATES PATENT OFFICE.

EMMET PLATTEN, OF GREEN BAY, WISCONSIN.

REFRIGERATING COUNTER.

Application filed June 6, 1927. Serial No. 196,843.

This invention relates to refrigerating counters.

Objects of this invention are to provide a novel form of refrigerating counter which is so constructed that a metal food receiving member is provided with a depressed portion below which and in contact with which a refrigerating unit is placed, such refrigerating unit being a distinct and separate entity 10 from the counter itself.

Further objects of this invention are to provide a construction such as outlined above in which a removable refrigerating unit is employed, such unit being constructed in a 15 manner to permit its free sliding into and withdrawal from the remaining portion of the apparatus without requiring and dismantling whatsoever.

Further objects are to provide a novel form 20 of refrigerating counter in which a removable unit is yieldingly held in intimate metal to metal contact with the bottom of the counter and is formed primarily as a metal slab having outgoing and return conduits or 25 channels provided therein and communicating with the main cylinder of the refrigerating unit, such metal slab being yieldingly held between the metal bottom of a refrigerating counter and a metal retaining 30 plate yieldingly urged upwardly towards the bottom of the counter, such counter being open at one end to permit the free withdrawal laterally of the unit.

Embodiments of the invention are shown 35 in the accompanying drawings in which:

Figure 1 is a longitudinal sectional view through a counter showing the refrigerating unit in place with parts broken away;

Figure 2 is a transverse sectional view, 40 such view showing a portion of the counter with the bottom removed and showing the refrigerating unit with parts broken away;

Figure 3 is a transverse sectional view on the line 3-3 of Figure 2;

Figure 4 is a view corresponding to Figure 45 3 showing a modified form of construction;

Figure 5 is a transverse sectional view of a further modified form;

Figure 6 is a transverse sectional view of 50 the refrigerating unit removed.

Referring to the drawings, it will be seen that the refrigerating counter comprises a metal trough-like member or counter proper

having a metal bottom 1 and continuous side walls 2 integral with the bottom. These 55 side walls terminate in outwardly extending flanges 3 which are secured between the marginal strip 4 and the side walls 5 of the counter. If desired, any suitable insulating packing may be employed. 60

Below the bottom 1 of the counter a metal plate 6 is positioned by means of a plurality of bolts 7. These bolts are preferably threaded or otherwise secured to the bottom 1 of the counter and pass through apertures 65 in the plate 6. They are provided with helical springs 8 loosely surrounding their stems and urging the plate 6 upwardly towards the bottom 1.

The refrigerating unit comprises a metal 70 slab or plate 9 provided with outgoing ducts or channels 10 and return channels 11 communicating with each other and with a main cylinder 12. This main cylinder may be of the conventional type of certain well-known 75 refrigerating units and may be supplied in any suitable manner. Such cylinder is rigidly formed with the metal slab 9, so that they constitute a single removable unit which is handled as a single entity and which is 80 slipped in place between the yielding plate 6 and the bottom 1.

It is to be noted from Figure 1 that the bottom 1 of the counter is provided with an upwardly bulged portion 1' which fits the 85 cylinder 12. It is to be noted further that one of the vertical walls 5 of the counter is provided with an aperture 13 therethrough so that the refrigerating unit may be bodily 90 slipped into place through the aperture and between the plate 6 and bottom 1 of the refrigerating counter.

The plate 6 may be made either stiff or yielding. Obviously, if it is made of stiff and non-yielding material, the springs 8 95 are essential for the correct operation of the apparatus as otherwise the bolts 7 would have to be loosened to permit removal and replacement of the unit, although in certain installations this may be found sufficient. 100 Preferably, however, the plate is made yielding or else springs, such as indicated at 8, are employed or both of these expedients may be followed.

The space between the side edges of the 105 metal plate 6 and the metal bottom 1 of the

counter are closed by means of the metal bellows-like folded and yielding strips 14. These strips, as may be seen from Figure 3, are apertured for the passage therethrough of the bolts 7. They contact with the bottom 1 and the plate 6 and provide a yielding seal or joint between such members.

It is to be noted further that the metal plate for holding the unit in place may be 10 replaced by a metal plate of the type shown in Figure 4, and indicated by the reference character 15. In this form of the invention, the edge portions 16 of such metal plate are turned upwardly and outwardly, as shown, 15 and are apertured for the reception of the bolts 17. This provides a sufficient amount of spring to permit the insertion and removal of the refrigerating unit.

It is to be noted further that the refrigerating unit is a single bodily removable entity and that not only the outgoing channels, but also the return channels for the refrigerant, are formed in the metal slab, so that the maximum heat extraction occurs. In 25 addition to this, the relatively wide and long metal slab of the refrigerating unit contacts throughout its face with a metal to metal contact with the metal bottom 1 of the counter. It is apparent, therefore, that the 30 heat of the articles placed within the counter is actually conducted directly through the metal of the counter and is carried away by the refrigerating unit.

It is to be noted particularly that there 35 are no pipes or other portions of the apparatus which have to be freed from bolts or attaching means in the removal or replacement of the unit. Instead, the unit is merely slipped through the front aperture in the 40 counter and pushed into place or is as freely removed.

It will be seen also that the utmost cheapness of installation and repair is obtained by this invention.

45 Referring to the form shown in Figures 5 and 6, it will be noted that the refrigerating counter 1' has formed rigid therewith a metal casing or shell 18 which provides a compartment of rectangular contour below 50 the counter. This compartment opens through the side wall of the apparatus in the manner previously described and houses a removable refrigerating unit 19 similar to the refrigerating unit previously described 55 and provided with ducts or passageways 21 for the refrigerant.

It is to be noted however that this form of 60 invention contemplates the employment of a plurality of springs 20 of metal which are rigidly joined to the refrigerating unit or slab 19 and which normally are somewhat extended. However, when the unit is slid into 65 position within the casing below the counter, the springs are substantially flat, as they are compressed between the walls of the cas-

ing and the bottom of the counter. These metal springs are good conductors of heat and, consequently, form an efficient thermal connection or joint between the refrigerating unit and the metal bottom of the counter.

70 In Figure 5, the position of the springs is very much exaggerated in order to adequately show the several parts. It is, however, intended that it be understood that these springs are substantially flat when the unit is slid into place, as the springs are compressed, as described above. Thus, it will be seen that the springs constitute a multitude of low resistance paths through which the heat may travel from the bottom of the counter to the refrigerating unit.

75 It is to be distinctly understood that although the food receiving portion has been described as depressed, it nevertheless, in some cases, may be made flush with the upper portion of the counter.

80 Although the invention has been described in considerable detail, such description is intended to be illustrative rather than limiting as the invention may be variously embodied 90 and as the scope of such invention is to be determined as claimed.

I claim:

1. A refrigerating counter comprising a body portion having a metal food receiving 95 member provided with a bottom wall, a refrigerating unit comprising a main cylinder and a metal slab rigid therewith and provided with outgoing and return ducts communicating with such cylinder, and means 100 for yieldingly holding the metal slab in intimate metal to metal contact with the underside of the metal bottom of said counter.

2. A refrigerating counter comprising a 105 body portion having a metal food receiving member provided with a bottom wall, a refrigerating unit comprising a main cylinder and a metal slab rigid therewith and provided with outgoing and return ducts communicating with such cylinder, and means 110 for yieldingly holding the metal slab in intimate metal to metal contact with the underside of the metal bottom of said counter, said means consisting of a metal plate 115 yieldingly urging said unit against the bottom of such counter.

3. A refrigerating counter comprising a main body portion having a food receiving part, formed of metal, a metal plate spaced 120 downwardly below said food receiving part and yieldingly urged towards such food receiving part, and a removable refrigerating unit having a metal slab provided with refrigerant conducting ducts therein, said 125 slab being slid laterally into position between said food receiving part and said plate.

4. A refrigerating counter comprising a main body portion having side walls and 130

having a metal food receiving compartment provided with a bottom wall, a metal plate positioned beneath said bottom wall and spaced therefrom, one of said side walls having an aperture therethrough, and a removable refrigerating unit adapted to be passed through said aperture and positioned between said plate and said bottom. 5

5. A refrigerating counter comprising a body portion having side walls, one of said side walls being apertured and having a metal food receiving member provided with a bottom wall, a plate yieldingly urged towards the underside of said bottom wall, and a removable refrigerating unit consisting of a rigidly joined cylinder and a metal slab rigid therewith and provided with outgoing and return ducts communicating with said cylinder, said refrigerating unit being positioned between said plate and said bottom on opposite sides of said metal slab. 10 15 20

6. A refrigerating counter comprising a body portion having side walls, one of said side walls being apertured and having a metal food receiving member provided with a bottom wall, a plate yieldingly urged towards the underside of said bottom wall, 25

and a removable refrigerating unit consisting of a rigidly joined cylinder and a metal slab rigid therewith and provided with outgoing and return ducts communicating with said cylinder, said refrigerating unit being positioned between said plate and said bottom and being freely removable laterally of said counter through the aperture in its side wall, and a plurality of bellows-like yielding metal strips closing the gap between said metal plate and said bottom on opposite sides of said metal slab. 30 35 40

7. A refrigerating counter comprising a metal body portion adapted to receive food, said counter having side walls with one of said walls provided with an aperture, a removable refrigerating unit consisting of a metal rectangular member having apertures for the circulation of a refrigerant, and yielding means for thermally connecting said removable unit to said metal body portion, said unit being freely movable through said aperture. 45 50

In testimony that I claim the foregoing I have hereunto set my hand at Green Bay, in the County of Brown, and State of Wisconsin. 55
